(57) **CLAIM**

The ornamental design for a cleaning pen, as shown and described.

DESCRIPTION

FIG. 1 is a front and left side perspective view of a cleaning pen showing my design.

FIG. 2 is a rear and right side perspective view of the cleaning pen shown in FIG. 1.

FIG. 3 is a front elevational view of the cleaning pen shown in FIG. 1.

FIG. 4 is a rear elevational view of the cleaning pen shown in FIG. 1.

FIG. 5 is a left side view of the cleaning pen shown in FIG. 1.

FIG. 6 is a right side view of the cleaning pen shown in FIG. 1.

FIG. 7 is a top plan view of the cleaning pen shown in FIG. 1.

FIG. 8 is a bottom plan view of the cleaning pen shown in FIG. 1; and,

FIG. 9 shows a front and left side perspective view of the cleaning pen of FIG. 1, wherein a head of the cleaning pen is folded in a groove.

The broken lines in the drawings depict portions of the cleaning pen that form no part of the claimed design. The oblique line shading shown in the drawings indicates a transparent or translucent surface.

1 Claim, 9 Drawing Sheets
